UNITED STATES PATENT OFFICE.

CHRISTEN CHRISTENSEN, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

SWITCH LOCK.

Application filed August 8, 1923. Serial No. 656,442.

The present invention relates to electrical switches and particularly to improvements in locking mechanism therefor.

In high tension switches, or switches designed for outdoor installation, it is a common practice to mount the pivot terminal, which pivotally supports the switch blade, on one insulator, and to mount the other terminal, with which the blade contacts, on another insulator spaced from the first insulator, and both projecting from a common mounting base. These two insulators carry substantially the entire weight of the switch, and receive the stresses set up in the switch by its operation, and possibly some additional stresses transmitted from the line to the switch. Where these insulators are relatively high for handling high voltages, they are often subject to considerable deflection or displacement under the above weight and stresses, and this frequently displaces the terminals to such an extent as to bind or prevent the operation of the switch lock mechanism.

It is the fundamental object of the present invention to provide a switch lock which will remain positive and reliable in operation even under a relatively large deflection of the insulators and switch terminals. One structural feature by which this object is attained, is to have the lock mechanism engage over a longitudinal edge of the blade, whereby the blade can shift longitudinally throughout a substantially unlimited range without disengaging from the lock mechanism or otherwise interfering with the normal operation of the lock.

Another structural feature, tending toward the foregoing object, is the arrangement whereby the blade and locking jaws are guided together laterally in order to offset lateral deflections of the insulators or terminals.

Referring to the accompanying drawings wherein I have illustrated a preferred embodiment of my invention:—

Fig. 1 is a side elevational view of a switch embodying my invention, the central part of the switch being broken away;

Fig. 2 is an enlarged transverse sectional view taken on the plane of the line 2—2 of Fig. 1;

Fig. 3 is a longitudinal sectional view

taken on the plane of the line 3—3 of Fig. 2;

Fig. 4 is a side elevational view of a slightly modified form;

Fig. 5 is a transverse sectional view of a modified form of locking mechanism; and

Fig. 6 is a longitudinal sectional view taken approximately on the plane of the line 6—6 of Fig. 5.

The switch is erected upon an conventional form of base or supporting frame 8, which can be mounted on the pole top, switching tower, or in any other desired location. Rising from this base are two insulators 9 and 11, the upper end of the former carrying the hinge terminal 12, to which the switch blade 13 is pivoted, and the upper end of the latter carrying the contact terminal 14. Each terminal has extending therefrom a connecting lug or clip 15, to which are connected the opposite sides of the line 16.

The switch blade 13 comprises two spaced blades 13' engaging on opposite sides of the hinge terminal 12. A pivot bolt 17 passes through these switch blades and through the hinge terminal, having spring washers 18 engaging under each bolt head 80 and normally urging the switch blades into firm contact with the sides of the terminal 12. The other end of the blade unit carries a ring 19 extending out beyond the end of the blade unit, the eye in this ring forming a convenient grasping means for engagement by an operating pole having a hook end adapted to engage therein.

Extending upwardly on each side of the contact terminal 14 is a guiding horn 21, the throat 22 between which horns substantially coincides with the upper end of the contact terminal 14 so as to guide the two switch blades 13'—13' down on opposite sides of this terminal. Each guiding horn 21 comprises a rear or outer wall 23 and two forwardly extending side walls 24 which form vertical rectangular recesses 25 in the opposing faces of the guiding horn for receiving the detent members 26. Extending upwardly from the recess portion 25 is a curved horn consisting of a front web 27 having reinforcing ribs or flanges 28 extending backwardly along each edge of the web 27.

As shown in Fig. 2, the upper part of the

contact terminal 14 is reduced in thickness to form slots on each side between the terminal and opposing faces of the guiding horn 21, the switch blades 13'-13' being receivable in the slots. The scarfed-out sides of the terminal leave shoulders 29 which form positive stops for the inward movement of the switch blades 13'. The thicker portion below the shoulder 29 is formed 10 with a horizontal base 31 adapted to be attached to the terminal bracket or head 32 carried on the upper end of the insulator 11. The lower ends of the guiding horn 21 are placed in substantial contact with the sides 15 of the widened terminal portion, and these horns are each formed with a cross web or bar 33 for bolting to the terminal base 31. This web or bar 33 is provided with a bolt hole through which passes a bolt 34, the latter extending down through an aligned hole in the terminal base 31 and tapping into the mounting head 32 on the top of the insulator. The outer walls 23 of the horns are 20 cut away, as indicated at 35 to provide openings for manipulating the bolts 34 in securing the contact terminal and guiding horns to the mounting member 32.

The detent or locking function is performed by the two jaw members which are 30 mounted for pivotal motion in the rectangular recesses or pockets 25. The upper ends of these detent members 26 have inwardly extending jaws 36 which are adapted to hook over the upper longitudinal edges 35 of the blades 13'. From the jaws 36, the detent members are curved backwardly to form guiding horns 37 by which the switch blades 13' are guided over the terminal 14 and the detent members 26 are cammed 40 apart for permitting this engagement of the switch blades over the terminal. The detent members 26 are pivotally supported at their lower ends by providing pivot pins or studs 38 extending from each edge of the detent 45 member in the plane parallel to the switch blades. These pivot studs repose in arcuate slots 39 cut in the under sides of the guiding horns.

Each detent member 26 is preferably 50 urged against its respective blade member 13' by suitable spring mechanism, whereby an intimate firm contact is maintained between the blade 13' and terminal 14, and also 55 between the blade and the detent member 26. This spring mechanism may consist of springs arranged singly or in duplicate to apply a resilient pressure to the back of each detent member at one or more points. In the arrangement shown, an upper spring 60 41 bears against the back of each detent member adjacent the upper edge of the switch blade, having its end confined around a stud 42 projecting from the back of the detent member. The other end of the spring 65 is centered on an adjustable screw 43 thread-

ing through the wall 23 of the horn. By threading this screw 43 in or out, any desired pressure may be imposed on the detent member 26 for restraining the switch blade in position over the contact terminal 14. When two springs are employed for pressing the detent member 26 against its corresponding switch blade, the second spring is preferably arranged to bear against the detent member 26 at a point adjacent 70 the lower edge of the switch blade so as to distribute the spring pressure of the two springs across the entire width of the blade. Such a second spring is illustrated at 45 in Fig. 2, this spring bearing at its inner end 75 against a centering stud 46 projecting from the back of the member 26. This spring may be of adjustable pressure through the medium of an adjusting screw 43, or may be of fixed pressure, as desired. For illustrating an alternative arrangement I have shown the spring as being of fixed pressure, and in this case the outer end of the spring takes into a cupped recess 47 formed in the outer wall 23 of the guiding horn. The upper spring 41 may similarly be of fixed pressure setting by having its end seated in the upper cupped recess 47 and dispensing 80 with the screw 43.

It will be observed that by locating the 95 two jaws 26 in the same transverse plane as the contact terminal 14, and by applying spring pressure to the outer sides of these jaws acting inwardly against the switch blades, these jaws perform the secondary 100 function of firmly pressing the switch blades into intimate contact with the contact terminal for effective electrical connection, in addition to their function of locking or restraining the switch blades. A uniform application of the spring pressure across the 105 width of the switch blade is secured by providing a slight amount of play between the pivot studs 38 and the arcuate slots 39 in which they are confined. This lateral play 110 allows each detent member 26 to have a lateral translational motion whereby the spring pressure is operative to shift the detent member into firm pressure contact with the switch blade across its entire width. This spacing 115 between the pivot stud and its bearing recess 39 is indicated at 40.

The jaws or detent members 26 may operate as a friction or spring lock, or as a positive lock, depending upon the requirements 120 of the situation.

Where a spring lock is desired, the surfaces 36 are sloped at an angle, substantially as shown in Fig. 2, so that a sharp outward jerk on the switch blade is operative to cam 125 the locking members 26 apart and permit the switch blades to be drawn out over the end of the contact terminal 14. The restraint offered by these surfaces 36 to opening movement of the switch blade can be widely va- 130

ried by changing the angle of these surfaces 36, and by threading the adjusting screws 43 in or out to increase or decrease the pressure on the outer ends of the locking members 26. Thus by changing the slope of the surface 36 to a very abrupt wedge and increasing the pressure of the cooperating spring 41 the restraint opposed to opening motion of the switch may be made to closely 10 approach that of a positive lock.

When a positive lock is desired, means must be provided for releasing this positive lock before the switch blade can be withdrawn. An exemplary form of means is 15 illustrated in Figs. 5 and 6. As shown in Fig. 6, it will be noted that the detent surfaces 36' are cut at right angles to the locking jaws to hook over the outer edges of the switch blades 13' and positively lock these 20 switch blades in against the contacting terminal. The jaw members 26 are separated by a lock releasing member 51 which is pivoted on a pivot pin 52 extending through the switch blades 13' adjacent their outer 25 ends. A pivot lug 53 extends down from the releasing member 51 between the switch blades, and receives the pivot pin 52. A ring 54 extends from the outer end of the switch releasing member 51 for receiving the hook 30 on the end of the operating pole. The inner end of the lock releasing member is curved down between the guiding horns 21 and carries a block or separating member 55 at its lower end. This separating member 35 is adapted to be forced down between the curved horns 37 on the upper ends of the jaws 26, whereby the jaws are cammed apart and the locking shoulders 36' are forced to the sides of the switch blades for 40 permitting the latter to be withdrawn. This will follow as a natural sequence resulting from an upward or outward pull exerted on the ring 54 through the switch operating pole. The initial effort will force the separating block 55 down between the curved horns 37, so as to separate the locking jaws, 45 after which the continued pull on the pole will draw the switch blades out over the end of the contact terminal 14.

50 While I have shown and described my invention in particular detail it will be apparent that various and many modifications may be made without departing from the scope of my invention.

55 I claim:—

1. In a switch lock, the combination of a switch terminal, a pair of guiding horns lying on opposite sides of said switch terminal, a disconnect element comprising a pair of switch blades movable into position 60 between the sides of said switch terminal and said guiding horns, a pair of locking jaws pivotally supported between said guiding horns and said switch terminal, said 65 locking jaws having locking surfaces en-

gagable over the upper edges of said switch blades, and spring means between said locking jaws and said guiding horns.

2. In a switch lock, the combination of a switch terminal, a switch blade, a detent 70 member, said switch blade being adapted to move between said detent member and said switch terminal, spring means for pressing said detent member against said switch blade, and mounting means for said detent 75 member permitting a translational motion thereof to enable said detent member to exert its pressure contact across the entire width of said blade.

3. In a switch lock the combination of a switch terminal, a detent member, a switch blade movable between said detent member and said switch terminal, a pivotal mounting 80 for the lower end of said detent member, spring means normally urging said detent 85 member against said switch blade, said pivotal mounting permitting a slight translational motion of the lower end of said detent member.

4. In a switch, the combination of a switch 90 terminal, a pair of guide members rising from opposite sides of said switch terminal, a disconnect element comprising a pair of switch blades engageable upon opposite sides of said terminal, a locking jaw pivotally connected to each of said guiding members, a spring tending to move said locking jaw towards said switch terminal, and means carried by said guide members for adjusting the pressure of said spring. 95

5. In a switch, the combination of a switch terminal having a base member, a pair of guiding horns, one rising on each side of said switch terminal, bolts securing said guiding horns to the base portion of said switch terminal, a pair of locking jaws between said switch terminal and said guiding horns, each of said locking jaws having pivot studs extending therefrom and engaging in bearing slots, a cam surface on the upper end of each of said locking jaws, a locking surface on the inner side of each of said locking jaws engageable over the edge of the corresponding switch blade, and spring means between each of said locking jaws and the adjacent 100 guiding horn. 105

6. In combination, a terminal, a blade for contacting the said terminal, a locking element for locking the blade in engagement with the terminal and resilient means acting 110 in a plane substantially at right angles to that of the blade for urging the locking element into tight engagement with the blade to cause the blade to be pressed into firm contact with the terminal. 115

7. In combination, a switch terminal, a floating switch element including a pair of blades adapted to be moved into engagement with the said terminal, means for guiding the movement of the blades into engagement 120 125 130

with the terminal, means for locking the blades in engagement with the terminal, and independent resilient means positioned intermediate the guiding means and the locking means for urging the locking means into engagement with the terminal.

8. In combination, a contact member, a locking member having free movement toward and away from the contact member, a switch blade operating between said members in contact therewith, and yielding means urging the locking member toward the blade and holding it flat against the blade.

15 9. In combination, a contact member, a locking member having rectilineal movement toward and away from the contact member, a switch blade operating between said members in contact therewith, and yielding means urging the locking member toward the blade.

10 10. In combination, a contact member, a locking member movable toward and away from the contact member, a switch blade operating between said members in contact therewith, and yielding means urging the locking member toward the blade, said locking member fitting flat against the blade and firmly contacting therewith throughout the width of the blade.

15 11. In combination, a contact member, a blade having an opening receiving said member, the blade contacting with the lateral faces of the contact member, locking members at opposite sides of the contact member

and movable toward and away from the same, and yielding means urging the locking members toward the contact member, said locking members contacting with the lateral faces of the blade and exerting pressure thereon holding the blade in contact with the lateral faces of the contact member.

12. In combination, a contact member, a blade having an opening receiving said member, the blade contacting with the lateral faces of the contact member, locking members at opposite sides of the contact member and movable toward and away from the same, and yielding means urging the locking members toward the contact member, said locking members contacting with the lateral faces of the blade throughout the width thereof and exerting pressure thereon holding the blade in contact with the lateral faces of the contact member.

13. In combination, a contact member, a blade having an opening receiving said member, the blade contacting with the lateral faces of the contact member, locking members at opposite sides of the contact member, said locking members being loosely mounted for rocking and rectilineal movement toward and away from the contact member, and yielding means urging the locking members toward the contact member and into contact with the lateral faces of the blade.

In witness whereof, I hereunto subscribe my name this 30th day of July, 1923.

CHRISTEN CHRISTENSEN.
